BAR TABLE

Jasper M. Rowland, 2977 Vesper Drive,
Akron, Ohio 44313

Filed Mar. 27, 1967, Ser. No. 6,387

Term of patent 14 years

(Cl. D33—14)

FIG. 1

FIG. 2

FIG. 3

FIG. 4

FIG. 1 is a perspective view of a bar table embodying my new design.

FIG. 2 is an end view thereof.

FIG. 3 is a plan view thereof, and

FIG. 4 is a side view thereof.

The elements shown by the dotted lines in the figures are for illustrative purposes only.

I claim:

The ornamental design for a bar table, as shown and described.
